UNITED STATES PATENT OFFICE.

LOUIS G. MERRITT AND KENNETH E. BERRY, OF LOCKPORT, NEW YORK, ASSIGNEES
TO MERRITT MANUFACTURING CO., OF LOCKPORT, NEW YORK, A CORPORATION OF
NEW YORK.

VENEER DRIER.

Application filed July 9, 1921. Serial No. 483,407.

To all whom it may concern:

Be it known that we, LOUIS G. MERRITT and KENNETH E. BERRY, citizens of the United States, residing at Lockport, in the county of Niagara and State of New York, have invented certain new and useful Improvements in Veneer Driers, of which the following is a full, clear, and exact description, such as will enable others skilled in the art to which it appertains to make and use the same.

This invention relates to drying machines and in some of its details more particularly to drying machines especially adapted for drying veneer by application of heat thereto.

It is an object of the invention to provide an improved machine of the class mentioned which is light, compact, and automatic in operation, and particularly adapted for installation where the desired output is not very large.

Another object is to provide an improved drying machine of light and simple construction utilizing the application of heat and automatically applying pressure to avoid warping or bulging of the material treated and intermittently relieving the pressure so as to avoid checking or splitting.

Another object is to provide an improved drying machine of the class mentioned which is simple in construction, has few operating parts, is unlikely to get out of order, and is comparatively inexpensive in manufacturing costs.

Other objects will be in part pointed out in connection with the following detail description of an illustrative embodiment of the invention and will be in part obvious in connection therewith.

In the accompanying drawings wherein an illustrative but preferred embodiment of the invention is shown,

Figure 1 is a side elevation of a drying machine equipped with the invention, and

Fig. 2 is a transverse central sectional view thereof, parts being shown in end elevation.

Referring to the embodiment shown, the base 1 is preferably constructed of a pair of

cast metal side frames arranged side by side and secured in spaced relation by tie rods 2 and having planed upper surfaces for receiving and supporting the lowermost of a series of platens. This lowermost platen 3 is supported in stationary position on the base being secured in position by lugs 4 extending laterally therefrom. Resting upon each of these lugs is a bracket or post 5, there being four of these posts in the embodiment shown all of the same construction. The posts 5 are preferably of cast metal each being provided with longitudinal and transverse members providing a light strong construction. Recesses are provided at the upper and lower extremities of the posts, the lower recesses receiving the lugs 4 of the stationary platen, while the upper recesses are adapted to receive the lugs of a superposed platen. The longitudinal member at one side of the post is extended at its lower end and provided with an angular extension 6 bolted to the planed surface of the side frame. It will be seen that this construction secures platen 3 in stationary position.

A second platen 7 is spaced above the first and supported in normally stationary position upon the stationary posts 5, the lugs 8 at spaced portions of opposite lateral edges thereof engaging in the recesses at the upper extremities of the posts and supporting the platen in position so it may be freely lifted off its support, there being no obstruction to upward movement thereof. It will be noted that there is no positive connection between the platen 7 and the post, the former resting freely upon the latter.

A platen 9 is movably supported between platens 3 and 7, being provided with lugs 10, similar to lugs 4 and 8, engaging in yokes 11 formed in brackets 12, and being suitably secured thereto as by set screws as shown. A bracket 12 is provided at each side of the machine and each has yokes 11 spaced at opposite extremities thereof for receiving the platen lugs. Each bracket is also provided at opposite extremities with downwardly extending pedestals 13 and 14 having lower terminal plates, 15 for cooperating with the

operating mechanism. The movable platen 9 is spaced between the other two platens so as to provide spaces above and below for the reception of the veneer or other material which is to be treated.

Since the movable platen 9 is directly movable through operation of the operating mechanism, as described below in detail, it may be regarded as the active platen as distinguished from the platens 3 and 7, which may be designated as the inactive platens.

Guiding means for preventing longitudinal movement of the movable platen in the operation of the machine is provided by lugs 16 on posts 5 adapted to engage with lateral faces of the yokes 11 to prevent movement in one direction, while a flange 17 extending inwardly from the inner surface of the side bar of the bracket 12 is adapted to engage the inner face of the left post, as appearing in Fig. 1, to prevent longitudinal movement in the opposite direction.

All of the platens are of similar construction, having upper and lower parallel walls providing upper and lower external faces for contacting with the veneer, and an inner compartment for receiving the heating medium which is preferably steam. Each platen may be constructed in two or more separate sections, adjacent sections being provided at their edges with complementary grooves and projections, as shown at 18, which interengage and hold the sections securely in relative positions, while lugs 19 extending from the lateral edges for receiving bolts are employed to secure the sections together. Supporting posts 20 are also provided between the opposite walls of the platen, as many of these posts being provided as are necessary for supporting the platen walls.

The operating mechanism for the movable platen comprises mechanism at opposite sides of the machine, and inasmuch as the mechanism at both sides is similar the description of that of one side only will be necessary. As shown in Fig. 1 two oppositely disposed bell crank levers 21 are pivotally mounted as at 22 to the side frame of the base, the lateral arms thereof being reversely disposed from the pivotal mountings and having terminal bifurcations thereon for receiving rollers 23, and the downwardly extending spaced arms are also provided with similar terminal bifurcations for receiving rollers 24. Rollers 23 are disposed so as to contact with the pedestal plates 15 of brackets 12 while rollers 24 are arranged to cooperate with a driving cam wheel 25 suitably mounted in bearings in the side frame 1. This driving cam wheel is preferably circular and has symmetrically arranged cam lobes 25' disposed between the downwardly extending arms of the bellcrank lever the faces of the cam lobes engaging

the rollers 24. By this arrangement the lateral thrust or reaction on the cam wheel and bearings is equalized, and wear and friction on the bearings reduced to a minimum. The cam wheel is provided with a peripheral worm wheel 26 meshing with a worm 27 or 28 carried on a transverse shaft 29 rotatably mounted in bearings 30 in the side frames. The worms 27 and 28 are spaced on the shaft 29 and oppositely threaded so the longitudinal thrust on the shaft, caused by reaction of the worm wheels, is equalized so there is comparatively no thrust upon the bearings 30 of the shaft. This is an advantageous arrangement due, among other reasons to the fact that friction and wear on the bearings are materially reduced, and the operating parts maintained in accurate alignment. The shaft 29 is connected for rotation by a motor 31 through suitable reduction gearing 32.

Steam or other heating medium may be conducted to the interior of the respective platens by a suitable system of piping as indicated in Fig. 1. The platens 3 and 7 are supplied by pipe 33 having branches 34 leading to the respective platen sections. These branches are fitted with extension joints 35 for permitting relative movement of these two platens. Similarly the movable platen 9 is supplied with steam by pipe 36 having branches 37 leading to the respective platen sections. Suitable drain or exhaust pipes (not shown) may also be provided.

The operation of the above described mechanism, which will be largely obvious, is substantially as follows:

Veneer or other material to be dried is loaded into the spaces above and below the movable platen to the desired amount. Steam is admitted to the platen and the driving motor started. Operation of the motor through the reduction gearing causes a slow measured rotation of the cam wheels 25 rocking the bellcrank levers 21 about their pivots and raising the movable platen through engagement of the rollers 23 with plates 15 of brackets 12.

Slow and steady upward movement is thus given to the movable platen and when the veneer in the space thereabove comes into contact with the lower surface of the upper platen 7 the latter may be lifted from its supports on posts 5 the weight thereof then being carried by the veneer. Heat will then be applied to the veneer from both contacting platens and the weight exerted thereon by the upper platen tends to prevent bulging and warping thereof, while the heat causes rapid drying. As the veneer dries a certain shrinkage takes place and checking or splitting thereof might result if the pressure of the upper platen were permitted to continue for a long space of time. This

- is prevented, however, by the subsequent lowering of the movable platen as the cams continue to rotate and the weight of the upper platen is again supported on the posts 5. As the movable platen continues its downward movement the upper gap increases in size permitting air to circulate around the veneer therein and allowing the vapors to escape. The subsequent raising 10 of the movable platen forces the air and vapor out of the gap giving rise to a "breathing" effect, the air being drawn in as the space increases in size, and the air and vapor expelled as the spaces decrease in 15 size. The drying process is thus rapidly promoted while injurious effects upon the material are avoided. It will be seen also that the action in the lower veneer space is similar to that in the upper space, but in 20 this case pressure is exerted on the veneer by the weight of the movable platen resting thereon. In this case the movable platen will be arrested in its descent by contact of the lower face thereof with the veneer in 25 the lower space, and the rollers 23 will advance away from contacting position with the brackets 12. It will be noted that the lower platen 3 remains stationary throughout the cycle of operation of the machine. 30 As many changes could be made in the above construction and many apparently widely different embodiments of this invention could be made without departing from the scope thereof, it is intended that all 35 matter contained in the above description or shown in the accompanying drawings shall be interpreted as illustrative and not in a limiting sense.
- It is also to be understood that the language used in the following claims is intended to cover all of the generic and specific features of the invention herein described, and all statements of the scope of the invention which, as a matter of language, 45 might be said to fall therebetween.
- Having described our invention, what we claim as new and desire to secure by Letters Patent is:
1. In a veneer drying apparatus, in combination, a base, a stationary drying platen mounted on said base, a movable drying platen adapted to cooperate with said stationary platen, brackets connected to said movable platen, and means for engaging 50 said brackets for automatically oscillating said movable platen.
  2. In a veneer drying apparatus, in combination, a base, a stationary drying platen mounted on said base, a movable drying platen adapted to cooperate with said stationary platen, brackets connected to said movable platen, and means including a bell-crank lever engaging said bracket for automatically oscillating said movable platen. 60
  3. In a veneer drying apparatus, in combination, a base, a stationary drying platen mounted on said base, a movable drying platen adapted to cooperate with said stationary platen, brackets connected to said movable platen, and means including a 70 continuously rotating cam for oscillating said movable platen.
  4. In a veneer drying apparatus, in combination, a base, a stationary drying platen mounted on said base, a movable drying platen adapted to cooperate with said stationary platen, brackets connected to said movable platen, means including a bell-crank lever engaging said bracket for automatically oscillating said movable platen 75 and means including a continuously rotating cam for automatically oscillating said bell crank lever and movable platen. 80
  5. In a veneer drying apparatus, in combination, a base, a stationary drying platen mounted on said base, a movable drying platen adapted to cooperate with said stationary platen, a bracket connected to said movable platen, bellcrank levers adapted to engage said bracket for moving said movable platen, and a cam having symmetrical oppositely disposed cam faces engaging the arms of said bellcrank levers for operating the same. 85
  6. In a drying apparatus, in combination, a base, a drying platen mounted on said base, stationary brackets carried by said base, a second drying platen freely supported upon said brackets, and a movable platen adapted at times to lift said second platen 90 from its supporting brackets. 95
  7. In a drying apparatus, in combination, a base, a stationary drying platen mounted on said base, brackets carried by said base, a second drying platen freely supported upon said brackets, a movable platen adapted at times to lift said second platen from its supporting brackets, and means for supporting the movable platen upon said stationary platen. 105 110
  8. In a veneer drying apparatus, in combination, a base, a stationary drying platen mounted on said base, a second drying platen freely supported by said base and spaced from said stationary platen, and a movable drying platen oscillatably mounted between said first mentioned platens. 115
  9. In a veneer drying apparatus, in combination, a base, a stationary drying platen mounted on said base, a second drying platen freely supported by said base and spaced from said stationary platen, a movable platen disposed between said first mentioned platens providing spaces above and below for receiving veneer, and means 120 whereby pressure is alternately applied to the veneer in said spaces. 125
  10. In a veneer drying apparatus, in combination, a base, a drying platen mounted on said base, stationary brackets carried by 130

10 said, base, a second drying platen freely supported by said brackets and spaced from said first mentioned platen, a movable platen disposed between said first mentioned platens 5 providing spaces above and below for receiving veneer, and means whereby said second drying platen is caused to rest upon the veneer in one of said spaces to apply pressure and heat thereto and subsequently said movable platen is caused to rest upon the veneer in another space to apply pressure and heat thereto.

11. In a veneer drying apparatus, in combination, a base, a drying platen mounted on said base, brackets carried by said base and resting upon said stationary platen, a second platen freely supported on said brackets and spaced from said first mentioned platen, a movable platen disposed between said first 20 mentioned platens and a bracket juxtaposed to said first mentioned brackets for movably supporting said movable platen.

12. In a veneer drying machine, in combination, a movable platen and means for moving said platen including a driven shaft having a right hand worm and a left hand worm at spaced portions thereof.

13. In a veneer drying machine, in combination, a movable platen and means for moving said platen including levers at opposite sides of said machine and oppositely disposed cams adapted to engage said levers to move said platen.

14. In a veneer drying machine, in combination, a movable platen, means for moving said platen including levers at opposite sides of said machine and oppositely disposed cams adapted to engage said levers to move said platen and a driven shaft having 40 right hand and left hand worms at spaced portions thereof for driving said cams.

15. In a veneer drying machine, in combination, a movable platen, a platen mounted on stationary bearings, means for moving said movable platen operatively connected at spaced portions thereof, said platen moving means including a motor driven shaft having a plurality of driving connections to said platen moving means.

16. In a veneer drying machine, in combination, a movable platen, means for moving said platen operatively connected at spaced portions thereof, and a motor driven shaft having a plurality of driving connections to said platen moving means said driving connections being arranged to equalize the thrust upon said shaft.

17. In a veneer drying machine, in combination, spaced platens mounted on stationary bearings, and an intermediate platen mounted on movable bearings.

18. In a veneer drying machine, in combination, spaced platens mounted on stationary bearings, an intermediate platen 65 mounted on movable bearings, bellcrank

levers operatively connected with said movable platen and a cam for operating said bellcrank levers.

19. In a veneer drying machine, in combination, a movable platen, a pair of bellcrank levers mounted in reverse positions, and a cam engaging said bellcrank levers to simultaneously operate the same to oscillate said platen.

20. In a veneer drying machine, in combination, a movable platen, a pair of bellcrank levers having arms operatively connected with said platen and angularly extending arms, and operating means engaging said angularly extending arms.

21. In a veneer drying machine, in combination, a series of platens arranged side by side, a stationary bracket for supporting certain of said platens, and a movable bracket for supporting certain of said 85 platens.

22. In a veneer drying machine, in combination, a series of platens arranged side by side, a stationary bracket for supporting certain of said platens, a movable bracket for supporting certain of said platens and means whereby said brackets are relieved at intervals of the weight of said platens.

23. In a veneer drying machine, in combination, a series of platens arranged side by side, a stationary bracket for supporting certain of said platens, a movable bracket for supporting certain of said platens and means operatively associated with said movable bracket for moving one of said platens.

24. In a veneer drying machine, in combination, a movable platen and means for moving said platen, including spaced worm wheels with driving worms therefor.

25. In an apparatus of the nature described, in combination, an active platen, a plurality of horizontal idle platens spaced from each other sufficiently to leave between them a space greater than the thickness of said active platen, at least one of said idle platens being supported to permit upward and downward movement thereof, said active platen being disposed between said idle platens and adapted to rest by gravity on one of the latter, and means for intermittently reciprocating said active platen to cause it to bear upward against and lift the next higher idle platen, and then to descend until the lifted idle platen is again engaged by and rests on its support and until the active platen rests upon the next lower idle platen.

26. In an apparatus of the nature described, in combination, an active platen, supports for the active platen connected thereto to provide an active platen unit movable upwardly and downwardly, a plurality of horizontal idle platens spaced from each other sufficiently to leave between them spaces greater than the thick- 130

- ness of said active platen, at least one of said idle platens being supported to permit upward and downward movement, said active platen being disposed between said idle platens and adapted to rest by gravity on one of the latter, and means for periodically reciprocating said active platen unit to cause said active platen to bear upwardly against and lift the next higher idle platen, and then to descend until the lifted idle platen is again engaged by and rests on its supports and until said active platen rests upon the next lower idle platen. 50
27. In an apparatus of the nature described, in combination, an active platen, a plurality of horizontal idle platens spaced from each other sufficiently to leave between them a space greater than the thickness of said active platen, at least one of said idle platens being supported to permit upward and downward movement thereof, said active platen being disposed between said idle platens and adapted to rest by gravity on one of the latter, means for intermittently reciprocating said active platen to cause it to bear upward against and lift the next higher idle platen, and then to descend until the lifted idle platen is again engaged by and rests on its support and until the active platen rests upon the next lower idle platen, and means for heating said platens. 60
28. In an apparatus of the nature described, in combination, an active platen, supports for the active platen connected thereto to provide an active platen unit movable upwardly and downwardly, a plurality of horizontal idle platens spaced from each other sufficiently to leave between them spaces greater than the thickness of said active platen, at least one of said idle platens being supported to permit upward and downward movement, said active platen being disposed between said idle platens and adapted to rest by gravity on one of the latter, means for periodically reciprocating said active platen unit to cause said active platen to bear upwardly against and lift the next higher idle platen, and then to descend until the lifted idle platen is again engaged by and rests on its supports and until the active platen rests upon the next lower idle platen. 65
29. In an apparatus of the nature described, in combination, an active platen, a plurality of horizontal idle platens spaced from each other sufficiently to leave between them a space greater than the thickness of said active platen, at least one of said idle platens being supported to permit upward and downward movement, said active platen being disposed between said idle platens and adapted to rest by gravity on one of the latter, a rotary shaft in operative relation with said active platen to periodically reciprocate the same and cause it to bear upwardly against and lift the next higher idle platen, and then to descend until the idle platen is again engaged by and rests on its supports and until the active platen rests upon the next lower idle platen, and means for heating said platens. 70
30. In an apparatus of the nature described, in combination, an active platen, a plurality of horizontal idle platens, upright posts formed for supporting certain of said platens providing a space between said idle platens greater than the thickness of said active platen, said active platen being disposed between said idle platens and adapted to rest by gravity on one of the latter, and means for periodically reciprocating the active platen to cause it to bear upward against and lift the next higher idle platen and then to descend until the lifted idle platen is again engaged by and rests on its supports, and until the active platen rests upon the next lower idle platen. 75

In testimony whereof we affix our signatures, in the presence of two witnesses.
